UNITED STATES PATENT OFFICE.

PATRICK H. MACK, OF BRADFORD, PENNSYLVANIA, ASSIGNOR TO OIL WELL SUPPLY COMPANY, OF PITTSBURGH, PENNSYLVANIA, A CORPORATION OF PENNSYLVANIA.

GAS-CONTROL ATTACHMENT FOR PACKERS.

Application filed January 29, 1924. Serial No. 689,305.

To all whom it may concern:

Be it known that I, PATRICK H. MACK, a citizen of the United States, residing at Bradford, in the county of McKean and State of Pennsylvania, have invented certain new and useful Improvements in a Gas- 5 Control Attachment for Packers, of which the following is a specification.

This invention is for a combination letting-in tool and control head for oil or gas well packers.

In the pumping of oil wells, gas accumulates in the hole below the packer. A certain amount of pressure is desirable as it aids the pump valves to operate to better 15 advantage. An excess of pressure must be avoided, however, or the pump will not operate efficiently. Consequently, it is desirable to provide means operable at will for 20 controlling the gas pressure.

The present invention proposes to provide a combined letting-in tool and control head applicable to present forms of packers. This device, when applied to a packer, secures the 25 packer to the well tubing, including the letting-in pipe, and may be used to set the packer in the usual way. The attachment has relatively movable parts, by means of 30 which the opening and closing of ports may be effected for letting the gas escape or for preventing its escape.

My invention may be readily understood by reference to the accompanying drawings, in which:

35 Fig. 1 is a longitudinal section through the combined letting-in tool and control head, showing the gas escape ports opened and illustrating the manner in which the invention is applied to an ordinary packer; 40 Fig. 2 is a similar view, showing the ports closed;

Fig. 3 is a transverse section in the plane of line III—III of Fig. 1; and

45 Fig. 4 is a transverse section in the plane of line IV—IV of Fig. 1.

In the drawings, 5 designates the body of the control head, particularly the lower connecting portion, adapted to screw onto the top of a standard packer A, in place of the usual upper member, and which may be turned to expand the packing B by being screwed down on the body of the packer, although the packing B is generally expanded by other means at the bottom of the body,

without turning member 5. The connection has a neck portion 6 of less diameter than the main part of the body, and in the inwardly sloping shoulder 7, between the wide bottom parts and reduced neck, are a plurality of ports 8. These ports are made as 60 large as possible to offer a minimum resistance to the flow of gas, the connecting webs 8^a between the ports being as narrow as possible, consistent with strength.

In the neck 6, are longitudinally extending slots or grooves 9. Slidably telescoping over the neck or extension 6 is a valve member 10 having a tapered lower end part 11 adapted to cooperate with the inwardly sloping top of the connector 5.

Passing through the valve member 10, a little above its lowermost end, are radial pins or screws 12, whose inner ends project into grooves 9, providing a spline, by means of which the valve and connector are slidably but non-rotatably joined. The sliding movement of the sleeve or valve 10 in an upward direction is limited by contact with the upper ends of slots 9, as shown in Fig. 1, these slots terminating below the upper end 70 of the neck. Screws 12 are provided with enlarged heads 12^a, which prevent the screws from being turned into binding engagement 75 with the slots.

At the upper end of the sleeve or valve member 10 is a reduced joint portion, interiorly threaded at 13, to engage a letting-in pipe 14. The upper part of the member 10 also interiorly threaded at 15, to receive the upper end of section 17 of the well tubing. Section 17 is preferably a short section, carrying a coupling sleeve 18 at its lower end, to which the upper end 19 of the next section of tubing is connected.

One of the chief advantages of this arrangement is that the upper end of the coupling sleeve 18 may be brought against the lower end of the neck portion 6 when the packer is being lowered or being pulled, as shown in Fig. 1, relieving pins 12 from all 95 or part of their work in limiting the upward movement of the valve member, and providing a safety check against the parts becoming detached if the pins 12 should shear.

A compression spring 20 may be interposed between the upper end of tubular extension 6 and the contracted upper part of

sleeve 10, the spring surrounding the tube section 17. This spring functions to urge the valve or sleeve member 10 upwardly. Its principal advantages is in serving to hold the valve open when the packer is being let into the well, tending to overcome any tendency of the valve to close, due to the packer becoming momentarily hung or caught in the well, or due to the tendency of the valve, which is otherwise held open by gravity, from closing because of any slight friction there may be between the packer and the sides of the well, and because of the pressure of the upward flow of fluids in the well tending to resist the downward movement of the packer.

In operation, central head 5 is substituted for the usual threaded connector or head at the top of the standard packer. Letting-in tubing 14 is attached to the top of the valve member, the connections to the well tubing 17 previously having been made.

The packer is then lowered into the hole. The weight of the packer, which is free to slide up and down with respect to the valve member, normally tends to keep the parts in the position shown in Fig. 1. The spring 20 also tends to hold the parts in this position. The ports 8, being of the greatest possible size, allow a maximum of the fluids rising in the well to escape therethrough, so as to offer a minimum resistance to the setting of the packer in a well which has a heavy flow.

When the packer, which, for instance, may be of the common hook-wall type, has been lowered to the desired point, tube 14 may be rotated to set the packer in the usual way, this rotative movement being transmitted to the packer through the pin and slot connection. If desired, the attachment might be turned again, after the packer has been set, to screw it down on threads *a* on the packer, thereby compressing the rubber from the top.

By reason of the large port area of the attachment, the packer and attachment, when lowered as a unit into a well, with the valve open, offers a minimum resistance to the upward flow of fluid in the well. This is highly important in the packing off of high pressure wells where considerable difficulty has heretofore been encountered in lowering a packer against the upwardly flowing fluid. It also provides a simple control for the escape of gas after the packer is set, and is very useful where gaseous wells are being pumped, as it enables the desired pressure to be maintained in the well for the best action of the pump valves.

From the foregoing, it will be readily understood that the invention may be applied to standard packers without modification of their construction. Various changes and modifications may be made in the con-

struction and arrangement of parts in the present invention within the contemplation of my invention and under the scope of the appended claims.

The present construction is designed to be used for the same purpose as the construction shown in my copending application filed July 18, 1924, Serial No. 689,307.

I claim as my invention:

1. The combination with a hollow well packer, of a head having a gas escape port therein, a valve member carried by the head and movable relatively thereto for opening and closing said port, and tubing extending through the packer and connected with the valve member.

2. The combination with a hollow well packer, of a head thereon having a gas escape port therein and having a valve seat, a valve member telescopingly fitted over a part of the head and having a valve portion for cooperation with the seat, and means for slidably and non-rotatably connecting the valve member and head.

3. The combination with a hollow well packer having a packing element thereon, of a head screwed onto the packer and arranged to compress the packer when being turned in one direction, said head having a restricted neck portion and a valve seat and a gas outlet port, a valve member slidable over the neck having a valve portion adapted to cover said port and engage against said seat, and means for slidably and non-rotatably connecting the valve and head.

4. The combination with a hollow well packer having a packing element thereon, of a head screwed onto the upper end of the packer, said head having an upper part of decreased diameter and a shoulder having a port therein between said upper part and the main body of the head, a valve member telescoping over said upper part having means thereon adapted to seat on the shoulder to close the port, and means for slidably connecting the valve member and the head.

5. A gas pressure regulating attachment for packers comprising a head adapted to be secured on the packer, said head having upper and lower parts, the upper part being of less diameter than the lower one, a shoulder between the upper and lower parts having a port therein, a tube slidably passed through the upper part of the head, a valve member screwed to the top of the tube telescoping the upper part of said head and non-rotatable with respect thereto, and cooperating means on the valve and body for limiting the upward sliding movement of the valve.

6. A gas control attachment for packers comprising a head member having a central extension of reduced diameter, gas escape

ports in the head around the central extension, a valve member slidably engaging the extension and having means thereon for closing said ports, means providing a sliding non-rotating connection between the extension and valve member, a well tubing passed through the central extension connected at its upper end to the valve member, and means on the valve member to which a letting-in tube may be connected.

7. A gas control attachment for packers comprising a head member having a central extension of reduced diameter, gas escape ports in the head around the central extension, a valve member slidably engaging the extension and having means thereon for closing said ports, means providing a sliding non-rotating connection between the extension and valve member, a well tubing passed through the central extension connected at its upper end to the valve member, means on the valve member to which a letting-in tube may be connected, and a compression spring inside the valve member around the well tubing interposed between the upper end of said central extension and the top of the valve member.

8. A gas control attachment for packers comprising a head member having a central extension of reduced diameter, gas escape ports in the head around the central extension, a valve member slidably engaging the extension and having means thereon for closing said ports, means providing a sliding non-rotating connection between the extension and valve member, a well tubing passed through the central extension connected at its upper end to the valve member, means on said well tubing below said extension arranged to engage the under side of said head member to limit the upward movement of said valve member with respect to the head, and means on the valve

member to which a letting-in tube may be connected.

9. A gas control attachment for well packers comprising an interiorly threaded head member adapted to screw on the top of a packer, a hollow central extension carried by the head, gas escape ports in the head around the central extension, said central extension having a longitudinally extending slot therein, a valve sleeve fitted over the extension and having a valve portion for cooperation with the ports in the head, a pin on said valve sleeve engaging in the slot to slidably and non-rotatably connect the valve sleeve and head, a well tube section connected with the valve sleeve passing through said extension, and means on the sleeve valve member for connection with a letting-in tubing.

10. A gas control attachment for well packers comprising an interiorly threaded head member adapted to screw on the top of a packer, a hollow central extension carried by the head, gas escape ports in the head around the central extension, said central extension having a longitudinally extending slot therein, a valve sleeve fitted over the extension and having a valve portion for cooperation with the ports in the head, a pin on said valve sleeve engaging in the slot to slidably and non-rotatably connect the valve sleeve and head, a well tube section connected with the valve sleeve passing through said extension, a joint member on said section of well tubing below said head adapted to contact therewith to limit the relative upward movement of said section of tubing with respect to the head, and means on the sleeve valve member for connection with a letting-in tubing.

In testimony whereof I affix my signature.

PATRICK H. MACK.
